[57] ABSTRACT

A contactor characterized by fluid drive means within an insulating housing containing a plurality of corresponding pairs of stationary contacts and movable contacts movable between open and closed positions with respect to each other; at least two pneumatic or hydraulic cylinder motor means for moving the movable contacts between said positions, a remotely controlled actuator motor for directing fluid into corresponding sides of the cylinder motor means simultaneously, gas coolant means for directing currents of coolant gas onto each set of contacts in a direction aligned with the path of travel of the moving contacts, the gas cooling means comprising gas conduits leading to the top of the housing in which the gas inlet nozzles are provided for directing the coolant gas to each of said contacts when the contacts are in the closed position, and safety latch means for holding the movable contacts in the open or closed positions and preferably in the open position.

FLUID OPERATED ELECTRICAL CONTACTOR WITH CONTACT COOLANT MEANS

CROSS REFERENCE TO RELATED APPLICATIONS

This invention is related to the inventions disclosed in the applications of Kurt A. Grunert, Ser. No. 319,823, filed Dec. 29, 1972, Ser. No. 294,135, filed Oct. 2, 1972, and Ser. No. 199,473, filed Nov. 17, 1971.

BACKGROUND OF THE INVENTION

1. Field of the Invention

This invention relates to an electrical contactor having reversible fluid drive means for moving the movable contacts between open and closed positions.

2. Description of the Prior Art

Electric contactors of the type shown in U.S. Pat. No. 3,602,850, issued Aug. 31, 1971, to Kurt A. Grunert, are well known in the art. Among other things they comprise an insulating support and a bridge contact structure supported within the support by which movable contacts are moved between open and closed positions with respect to stationary contacts. The contactor also includes an electromagnetic means for moving the bridge contact structure between those positions. In some electrical control systems, it is desirable to modify the manner of movement of the bridge contact structure from strictly opening and closing the circuit to contact by the application of the necessary force to a movement where variable velocity control is available.

Associated with the foregoing is the ability to increase the electrical current capability or rating of the particular contactor involved by a substantial amount, such as from 250 amperes to 1,000 amperes, by increasing the pressure between the contacts in the closed position and by providing contact coolant means. Where the contacts are open and closed by fluid drive means, a single cylinder is satisfactory for many applications. However, to increase the cylinder size instead of increasing the number of cylinders, such as two cylinders instead of one, does not necessarily double the amount of contact force which is desirable for reducing the generation of heat between the contacts in the closed position. Moreover, increasing the size of cylinder results in some instability due to mechanical binding of the piston in the cylinder of larger diameter.

SUMMARY OF THE INVENTION

In accordance with this invention, it has been found that the foregoing problem may be overcome by providing a circuit interrupter structure comprising an electrically insulating housing, a plurality of sets of contacts within the housing and comprising stationary contacts and movable contacts movable between open and closed positions with the stationary contacts, a reversible fluid drive means comprising at least two fluid cylinders and pistons, the movable contacts being movable on a movable contact carrier, the pistons having piston shafts being operatively connected to the movable contacts for unison movement thereof, gas coolant means in the housing for directing currents of coolant gas onto each set of contacts, the gas coolant means comprising a gas conduit operatively connected to a

valve which valve is part of the fluid drive means for remotely controlling the direction of fluid into one or the other side of the fluid cylinder, and latch means comprising a movable latch member movable to a latch position to retain the contact carrier structure in the open position.

The advantage of the device in this invention is that it provides for more stabilized electrical switching control including the variable velocity control by doubling the amount of contact force to reduce the amount of contact heating, avoids mechanical binding which would otherwise occur with a single piston in a cylinder of larger diameter where one air motor is used, and where the reversible fluid drive means is pneumatic rather than hydraulic, air can be used for cooling the contact in the closed position, thereby increasing the initial rating of a particular circuit interrupter.

BRIEF DESCRIPTION OF THE DRAWING

FIG. 1 is a plan view of a three-pole contactor constructed in accordance with the principles of this invention;

FIG. 2 is a vertical sectional view taken along the line II-II of FIG. 1;

FIG. 3 is a vertical sectional view taken along the line III-III of FIG. 2; and

FIG. 4 is an elevational view taken along the line IV-IV of FIG. 1.

DESCRIPTION OF THE PREFERRED EMBODIMENT

In FIGS. 1 and 2 of the drawings, a three-pole contactor is generally indicated at 5. Inasmuch as the contactor is more particularly disclosed in U.S. Pat. No. 3,602,850, the description of the contactor herein is directed generally to the operating parts of the contactor with specific emphasis on the reversible fluid drive means which is the improvement over contactors for circuit interrupters of prior construction.

Generally, the contactor 5 comprises a housing 7 and a contactor structure 8 supported on the housing structure. The housing structure 7 comprises a base 9, a molded insulating intermediate housing portion 10 suitably secured to the base, and a molded insulating cover 11 suitably secured to the intermediate housing part.

Contactor structure 8 comprises reversible fluid drive means for moving the movable contacts of the contactor between open and closed positions. More particularly, the reversible fluid drive means comprises at least two and preferably a pair of cylindrical motors including a pair of cylinders 13, 14 (FIG. 3), similar pistons 15 (only one of which is shown in FIG. 2), upper and lower closures 17 and 19 and piston shafts 20 and 21. Guide pins 22 extend from the base 9, and separate coil kickout springs 23 are supported on each of the guide pins. The springs 23 are strong enough to override the frictional forces of the cylinders in case of air failure so as to make the system failsafe. A movable contact carrier 25 is provided to cooperate with the reversible fluid drive means in a manner to be hereinafter described. The contact carrier 25 comprises a connecting rod 27 that rests on ledges 29 and passes through a central opening portion of the carrier. Opening 31 is provided at opposite ends of the lower portion of the contact carrier and cooperate with the vertical guide pin 21 for guiding vertical movement of the contact carrier 25. The undersurface of the carrier rests upon

60
65

the upper end of the spring 23, whereby the contacts are biased in the open position when the reversible fluid drive means is not operating. However, use of the spring is optional or may be used for biasing the contacts in the fluid position, such as where the spring 23 is tensile instead of a compression spring.

The contactor 5 is a three-pole contactor with three bridging contact structures 35 supported on each of three insulating upright portions 33 of the contact carrier 25. Each of the bridging contact structures 35 comprises an elongated flat conductor 37 having a pair of contacts 39 fixedly secured thereto in a spaced relationship. The manner in which the bridging contact structure 35, the insulating contact carrier 25, and the tubular upright portions 33 are disposed and function as shown in patent No. 3,602,850. When the contact carrier 25 is lowered by the reversible fluid drive means, movable contacts 39 on the flat conductor 37 are brought into electrical contact or closed (broken line) position with the stationary contacts 41 which are located within the cover or insulating housing 11. The movable contacts 39 and the stationary contacts 41 are retained in the closed position by the piston 15 of the fluid drive means without the use of mechanical latches. Each stationary contact 41 is mounted on a separate stationary contact structure 43 which, in turn, is mounted on the inner end of one of two conductors 45. Each conductor 45 is part of a pole unit which is supported on the intermediate housing 10 by bolts 47. Solderless terminal connectors 49 are secured to the outer ends of the conductors 45 to enable connection of each pole unit to an electric circuit.

As shown in FIG. 2, the lower end of the contact carrier 25 is secured to the upper end of the shaft 20. For that purpose, the contact carrier includes a pair of connecting rods 27 and 28, the latter of which extends at right angles to the former. The opposite end portions of both rods 27 and 28 are secured to opposite sides of the contact carrier in the manner similar to that shown for the connecting rod 27. The connecting rods 27 and 28 have aligned openings for receiving the upper end portion of the shaft 20 and both openings are preferably threaded for engagement with said end portion. In addition, a lock washer 51 and a lock nut 53 are secured against the underside of the connecting rod 27. Accordingly, when the shaft 20 moves up the movable contacts 39 are moved to the open position. As shown in FIG. 2, when the shaft 20 moves down, the movable contacts are brought into closed positions with the stationary contacts 41.

The reversible fluid drive means including the cylinders 13, 14 are actuated by actuator means comprising a valve 55 (FIG. 3) for directing fluid into the cylinders on one or the other side of the pistons 15. For that purpose, the valve 55 is connected by a conduit 57 to a source of fluid, such as pressurized gas or liquid, depending upon whether the fluid motor comprising the cylinders 13, 14 is operated pneumatically or hydraulically. Supply conduits 59 and 61 extend in pairs from the valve 55 to opposite ends of the cylinders 13 and 14. The valve 55 may be manually operated, or is preferably operated by remote control in a conventional manner for which reason it is provided with a solenoid-operated valve member for which lead wires 63 and 65 are provided to transmit an electrical impulse to the solenoid in order to reverse the position of the valve and thereby direct fluid through one or the other of the lead

conduits 59 and 61 into opposite end portions of the cylinders 13 and 14.

The valve 55 may be one of the direct operating type that is disclosed in U.S. Pat. No. 3,251,378. Such valves are available for operation either by single solenoid with spring return or by two solenoids. A diagrammatic view of a valve having two solenoids is shown in FIG. 3 and comprises a valve chamber 71. As shown, the conduits 59 and 61 communicate with the chamber 71 and the conduit 57, leading from the source of fluid, also communicates with the chamber. A pair of solenoids 73 and 75 are located at opposite ends of the chamber 71 for moving the valve member 69 to direct fluid to either side of the piston 15. In the position shown the valve member 69 is located to direct fluid from the conduit 57 to the conduit 61 and into the cylinder 13 on the lower side of the piston 15. Fluid on the upper side of the piston 15 is exhausted through the conduit 59, the valve chamber 71, and a port 77. When the solenoid 75 is actuated, the valve member 69 is moved to the right whereby the fluid flow is reversed with the fluid from the lower side of the cylinder 13 being exhausted through a port 79. Both ports 77 and 79 lead to fluid supply reservoir (not shown).

The speed of opening and closing of the contacts is controlled separately by a pair of speed control screws 81 and 83 which are seated in the body of the valve 55. The inner end portions of the screws 81 and 83 extend into the exhaust ports 77 and 79, respectively, by distances dependent upon the speed conditions required. However, the screws 81 and 83 may be disposed in the conduits 59 and 61. As shown in FIG. 3, the screw 81 extends a lesser distance across the port 77 than the screw 83 extends across the port 79. Thus, the fluid flow from the lower portion of the cylinder 13 is slower than it is from the upper portion, whereby upon closing of the contacts 39 and 41 there is reduced contact bounce and reduced impact. The screws 81 and 83 may be set for varying positions within the ports 77 and 79 in order to vary the speed of opening and closing of the contacts within the range of from about 0.1 to about 10 feet per second. In addition to reducing contact bounce and impact it is necessary under some conditions to regulate the closing speed for timing reasons. Moreover, the opening speed may be adjusted for regulating the arcing intensity.

Gas coolant means are provided in order to direct a blast of a coolant gas, such as air, into the area of the stationary and movable contacts in order to cool the contacts and associated current bearing components. The blast of coolant gas is sustained at least during the time the contacts are opened if necessary to dissipate any heat generated while the contacts are closed. Thus, the electrical current carrying rating of the contactor is increased significantly, such as twofold, depending upon the flow rate and temperature of the coolant gas. For the contacts of each pole of the contactor, the gas coolant means comprises a pair of inlets or nozzles 85. As shown in FIG. 2, the nozzles 85 are disposed in a top wall 87 of the insulating housing cover 11. Each nozzle 85 is so disposed that it directs a continuous current of air onto the upper side of the assembly of the contacts 39 and 41. The coolant gas may flow continuously or only during the occasions when the contacts are in the closed position. Suffice it to say, the coolant gas is directed from the nozzles into the contact area and preferably in alignment with or substantially parallel to the

direction of travel of the movable contacts 39. However, the nozzles 85 may be disposed at another location in the insulating housing cover 11 so as to be directed at angles to the direction of travel of the contacts 39, but not perpendicular or normal to that direction. If the gas were directed perpendicular or normal to the direction of travel of the contacts 39, there would be the undesirable tendency of the arc to be blown back toward the contacts or contact support with resulting damage thereto. The nozzles 85 communicate with a plurality of interconnecting channels 89, 91 and 93 extending between the several nozzles or inlets 85 in a cover manifold 95. The cover manifold 95 is attached to the upper surface of the cover 11 in a suitable manner, such as screws 97, which cover manifold extends over the several nozzles 85 and channels 89, 91 and 93. The cover manifold 85 includes a gas conduit 99 that leads to the valve 55 that transmits coolant gas to the conduit 99 when the contacts 39 and 41 are closed. The cover 11 and the cover manifold 95 are composed of an electrical insulating material, such as polyester or phenolic resins.

As shown in FIG. 1 a latch member 101 is employed for additional safety and is attached (FIG. 4) to one side of the contactor. The latch member 101 is a mechanical device for use by another person such as an electrician or a maintenance man who is required to perform some duties when the contactor is in the open position as shown in FIG. 4. Employment of the latch member 101 prevents inadvertent actuation of the contactor by a person who may be unaware of a second person working on the line. The latch member 101 comprises a mounting bracket 103 and a latch 105. The mounting bracket 103 includes a pair of upright supports 107 and 109. As shown in FIG. 1, the latch 105 is a U-shaped member including spaced legs 111 and 113. The latch 105 is maintained in a retracted or unlatched position (FIG. 4) by coil spring 115. The legs 111 and 113 extend through and are slidably disposed in spaced pairs of aligned apertures in the upright supports 107 and 109. Similar retaining pins 117 are provided at the left end of each leg to prevent the latch 105 from being completely retracted from the mounting bracket 103.

In operation, the latch 105 is used when the contactor 5 is in the open circuit condition by advancing the latch to the latch position as shown in broken line in FIG. 4, whereby the legs 111 and 113 are disposed under the movable contact carrier 25. To prevent the springs 115 from retracting from the latch position to the unlatched position, one or both of the legs 111 and 113 are provided with a hole 119, which hole is shown

in broken-line position 119a when the latch 105 is in the advanced or unlatched position between the upright supports 107 and 109 as shown in FIG. 4. In that position the shackle of a padlock may be inserted in the opening 119a to prevent the traction of the latch from the latched position by anyone other than an individual having a key to remove the padlock.

Accordingly, the device of the present invention provides reversible fluid drive means comprising at least two fluid motors for actuating the movable contact carrier of a contactor between open and closed positions. In addition, the device provides for a coolant means directed preferably onto the movable contacts to enable operation of the contactor at a lower temperature and therefore at a higher rating. Finally, latching means for safety purposes is provided to prevent inadvertent closing of the contact.

What is claimed is:

1. A circuit interrupter structure comprising an electrically insulating housing, a plurality of sets of contacts within the housing and comprising stationary contacts and movable contacts movable between open and closed positions, an elongated contact carrier along which the sets of movable contacts are disposed in spaced relationship, reversible fluid drive means comprising at least two fluid cylinder and piston structures and having piston shafts connected to and at spaced positions along the elongated contact carrier, the fluid drive means comprising a remotely controlled valve mechanism directing fluid into one or the other side of the fluid cylinders uniformly so that the assembly of the elongated contact carrier and the sets of movable contacts is movable in a stable, non-binding manner.

2. The circuit interrupter structure of claim 1 in

which the fluid drive means comprise two fluid cylinder and piston structures.

3. The circuit interrupter structure of claim 1 in which the remotely controlled valve mechanism comprises means for adjusting the flow rate of the fluid into and out of said valve mechanism.

4. The circuit interrupter structure of claim 1 in which gas coolant means connected to said valve mechanism for directing currents of coolant gas onto each set of contacts in a direction aligned with the path of travel of the movable contacts are provided in the insulating housing, in which the fluid is a gas, and in which the gas coolant means comprises a gas conduit operatively connected to the valve.

5. The circuit interrupter structure of claim 1 in which the gas coolant means operates only when the contacts are closed.
